CIRCUIT INTERRUPTER

Winthrop M. Leeds, Forest Hills, Pa., assignor to
Westinghouse Electric Corporation, East Pitts-
burgh, Pa., a corporation of Pennsylvania

Application September 14, 1944, Serial No. 553,997

16 Claims. (Cl. 200—150)

1

This invention relates to circuit interrupters in general and, more particularly, to arc-extinguishing structures therefor.

My invention has particular application to circuit interrupters of the liquid-break type and for purposes of illustration my invention will be described in connection with such a type of circuit breaker.

The operating arrangement which I use in connection with my invention is related to the operating arrangements described in United States patent application filed August 15, 1944, Serial No. 549,576, now U. S. Patent 2,477,810, issued August 2, 1949 to Winthrop M. Leeds and James M. Cumming; and United States patent application filed August 31, 1944, Serial No. 552,133, now U. S. Patent 2,465,240, issued March 22, 1949 to Winthrop M. Leeds, the foregoing applications being assigned to the assignee of the instant application.

A general object of my invention is to provide an improved circuit interrupter in which interruption of the circuit therethrough is effected more rapidly than has been achieved heretofore.

A more specific object of my invention is to provide an improved circuit interrupter, in which the maximum break distance in a group of serially connected contact gaps is obtained with a minimum overall length.

Another object is to provide an improved circuit interrupter in which the ratio of insulation to conducting material in the lengthwise direction is very high when the contacts are in the open circuit position.

Another object is to provide an improved circuit interrupter in which the inertia of the rotating parts is reduced considerably over that which results in using straight line moving parts.

Another object is to provide an improved arc-extinguishing assemblage, comprising a plurality of arc-extinguishing units with improved operating means therefore.

Another object is to provide an improved circuit interrupter of the foregoing type in which, during the interruption of low currents, a relatively long pressure-generating arc is employed to effect fluid flow toward the interrupting arc.

Another object is to provide an improved circuit interrupter, the movable parts of which have a low moment of inertia to thus effect a very high opening accelerating movement of the movable contacts. Preferably, the construction is such that a plurality of serially related pressure-generating arcs are formed simultaneously with the establishment of a plurality of serially related

2

interrupting arcs, the pressure generated at the pressure-generating arcs being employed to effect fluid flow toward the interrupting arcs to effect the latter's extinction.

5 Further objects and advantages will readily become apparent upon a reading of the following specification taken in conjunction with the drawings, in which:

Figure 1 is an elevational view, partly in section, of a circuit interrupter embodying my invention and shown in the closed circuit position;

Fig. 2 is an enlarged fragmentary view, partially in section, of the lower portion of the left-hand arc-extinguishing assemblage shown in 15 Fig. 1, and taken substantially on the line II—II of Fig. 3, the parts being shown in the closed circuit position;

Fig. 3 is a side elevational view, partially in section, taken along the line III—III of Fig. 2;

20 Figs. 4 through 20 show plan views of insulating plates used in the construction of the arc-extinguishing units shown in Fig. 1;

Fig. 21 is a view in section taken along the line XXI—XXI of Fig. 22;

25 Fig. 22 is a vertical sectional view taken through a modified form of arc-extinguishing assemblage, the parts being shown in the closed circuit position;

Fig. 23 is a view in section taken along the line XXIII—XXIII of Fig. 24;

Fig. 24 is a vertical sectional view through a modified type of arc-extinguishing unit;

Fig. 25 is a vertical sectional view taken through another modified form of arc-extinguishing unit; and

30 Fig. 26 shows, in fragmentary manner, an operating arrangement for the contact construction shown in Fig. 25.

Referring to the drawings and more particularly to Fig. 1 thereof, the reference numeral 1 designates a tank filled to the level 2 with a suitable arc-extinguishing fluid 3, in this instance circuit breaker oil. Depending from the cover 4 of the tank 1 are two insulating bushings 5, 6 45 through which extend terminal studs 7, 8. The terminal studs 7, 8 have threadedly secured to their lower ends, respectively, contact feet 9, 10, the latter supporting identical arc-extinguishing assemblages generally designated by the reference numeral 11.

The two arc-extinguishing assemblages 11 are electrically interconnected in the closed circuit position of the interrupter, as shown in Fig. 1, by a conducting bridging member 12 which is reciprocally actuated in a vertical direction by an

insulating operating rod 13 which may be actuated by suitable mechanism, not shown.

Each of the arc-extinguishing assemblages 11 comprises a plurality of arc-extinguishing units generally designated by the reference numeral 14, the construction of which is more clearly shown in Figs. 2 and 3.

It will be observed from an inspection of Fig. 1 that the conducting bridging member 12 during the closing operation slides between disconnect fingers 15 to strike a cross-member 16 composed of a conducting material. At the opposed outer ends of the cross-members 16 are fixed insulating operating rods 17 extending axially of the arc-extinguishing assemblages 11.

Referring to Fig. 3, it will be observed that the operating rods 17 are pivotally connected at 18 to crank arms 19 which serve to rotate during the opening and closing operations a shaft 20 extending through each of the arc-extinguishing units 14 and on which is fixedly mounted a bridging contact 21 electrically interconnecting two stationary contacts 22, 23 associated with each arc-extinguishing unit 14.

The bridging contact 21 has a contact portion 24 at one end and a contact portion 25 at its other or upper end. The contact portion 24 separates from the stationary contact 23 to establish a pressure-generating arc indicated by the dotted line 26 of Fig. 3. The contact portion 25 separates from the stationary contact 22 to establish an interrupting arc designated by the dotted lines 27 of Fig. 3. Preferably, the stationary contacts 22, 23 are resiliently mounted by suitable spring means, not shown, within the stationary contact housings 28, 29 to provide the requisite contact pressure in the closed circuit position, as shown in Fig. 3. Conductors 30 electrically interconnect the lower stationary contact 23 of one unit 14 with the upper stationary contact 22 associated with the immediately adjacent unit 14.

It will, therefore, be apparent that in the closed circuit position of the interrupter, as shown by the full lines in Figs. 1, 2 and 3, that the electrical circuit extending therethrough comprises terminal stud 1, contact foot 9, stationary contact 22, bridging contact 21, lower stationary contact 23, conductor 30 through the next arc-extinguishing unit 14 in like manner to finally conductor 31 which electrically connects the lower stationary contact 23 associated with the bottom arc-extinguishing unit 14 with the disconnect fingers 15. The electrical circuit then extends through the conducting bridging member 12 and through the right-hand arc-extinguishing assemblage 11 in like manner to the terminal stud 8.

Associated with each arc-extinguishing unit 14 are a plurality of insulating plates shown more clearly in Figs. 4 through 20. Each arc-extinguishing unit 14 comprises a cylindrical tube 32 composed of insulating material of the requisite mechanical strength. Disposed within the tube 32 is an insulating sleeve 33 which holds in position a plurality of suitably shaped insulating plates to be hereinafter described. The top insulating plate is designated by the reference numeral 34 and has a configuration more clearly shown in Fig. 4 of the drawings. The plate 34 has a plurality of apertures 35 through which extend insulating dowel pins serving to hold the insulating plates in proper position with respect to each other. The plate 34 has an elongated aperture 36 formed therein through which extends partially the upper stationary contact 22 of the unit 14. The upper portion of the left-hand

end of the aperture or slot 36 comprises a plurality of pockets 37 which serve to retain a plentiful supply of oil adjacent the interrupting arc 27. At the lower portion of the left-hand end of the slot 36 is a restricted portion 38 into which the interrupting arc 27 may enter only during relatively low instantaneous values of arcing current.

Below the plate 34 is an insulating vent plate 39 having a configuration more clearly shown in Fig. 5. The vent plate 39 has a widened slot 40 which terminates in a vent opening 41. Below the plate 39 is an insulating plate 42 having a configuration as shown in Fig. 6. The plate 42 has a slot 43 formed therein which communicates with a slot 44 leading into a restricted portion 45.

Below the plate 42 is an insulating plate 46 shown more clearly in Fig. 7. The plate 46 has a slot 47 which communicates with a plurality of, in this instance six, pockets 48. Below the plate 46 is an insulating plate 49 shown more clearly in Fig. 8. The plate 49 has a slot 50 which communicates with a more restricted slot 51 leading at its left-hand end to a plurality of, in this instance six, pockets 48. Below the plate 49 is an insulating plate 52 having a configuration more clearly shown in Fig. 9. The plate 52 has a slot 53 formed therein which communicates through a passage 54 to a restricted portion 55. Below the plate 52 is a second venting plate 56 having a configuration more clearly shown in Fig. 10. The plate 56 has a slot 57 formed therein which communicates through a passage 58 to a vent opening 59.

Below the plate 56 is a plate 60 having a configuration more clearly shown in Fig. 11. The plate 60 has a slot 61 which communicates through a passage 62 to a restricted portion 63. Below the plate 60 is a plate 64 having a configuration more clearly shown in Fig. 12. The plate 64 has a slot 65 formed therein which communicates with a plurality of pockets 66. Below the plate 64 is a plate 67 having a configuration, as shown in Fig. 13. The plate 67 has an enlarged portion 68 which communicates by way of a passage 69 to a restricted portion 70. Below the plate 67 is a third venting plate 71 having a configuration more clearly shown in Fig. 14 of the drawings. The plate 71 has the enlarged portion 68 which communicates through passage 69 to a vented opening 72. Below the plate 71 is a plate 73 having a configuration, as shown in Fig. 15. The plate 73 has an enlarged portion 74 which communicates by way of a passage 75 with a restricted portion 76.

Below the plate 73 is a plate 77 composed of insulating material and having a configuration more clearly shown in Fig. 16 of the drawings. The plate 77 has an enlarged portion 78 removed therefrom which communicates by way of a passage 79 to a plurality of, in this instance six, pockets 80. Below the plate 77 is an insulating plate 81 having a configuration more clearly shown in Fig. 17 of the drawings. The plate 81 has a portion 74 removed therefrom which communicates by way of a passage 82 to a plurality of, in this instance six, pockets 80.

Below the plate 81 is a plate 83 having a configuration more clearly shown in Fig. 18. The plate 83 has an enlarged portion 84 removed therefrom which communicates by way of a passage 85 to a restricted stop 86. Below the plate 83 is positioned a plate 87 having a configuration more clearly shown in Fig. 19. The plate 87 has an enlarged portion 88 removed therefrom having a recess 89 at its left-hand end. The plate 87 also

has a portion 90 removed therefrom. The bottom insulating plate of the stack is designated by the reference numeral 91 and has a configuration more clearly shown in Fig. 20 of the drawings. The plate 91 has an enlarged beveled portion 92 removed therefrom through which partially extends the lower stationary contact 23 of the unit 14. All of the plates have the apertures 35 formed therein through which extend insulating dowel pins holding the several plates in position.

The operation of the interrupter will now be explained. During the opening operation, the conducting bridging member 12 moves downwardly to permit a downward movement of the cross-member 16 and operating rod 17. The downward movement of the operating rods 17 causes a counterclockwise rotation of the crank arms 19 and hence a counterclockwise rotation of the bridge contact 21 to cause a separation of the contacts 22, 25 and 23, 24. The separation of the contacts 22, 25 establishes an interrupting arc 27 and the separation between the contacts 23, 24 establishes a pressure-generating arc 26. The pressure created at the pressure-generating arc 26 causes oil to flow in the direction as indicated by the arrows in Fig. 3 tending to bias the interrupting arc 27 into the restricted portions or restricted slots afforded by the plates 34, 42, 52, 60, 67, 73 and 83. During relatively high instantaneous values of arcing current, that is, during the peak of the alternating-current wave, the cross-sectional area of the interrupting arc 27 is too large to permit it to be forced by the oil flow from the pressure-generating arc 26 into the restricted slots or portions formed by the aforesaid enumerated plates. It is only during relatively low instantaneous values of arcing current, that is near a current zero at a time suitable for interruption, that the cross-sectional area of the interrupting arc 27 is sufficiently small to permit the oil flow from the pressure-generating arc 26 to force the interrupting arc 27 into the aforesaid restricted portions or slots. While the interrupting arc 27 is in these restricted slots, it is subjected to turbulence and deionizing activity as provided by the oil flow passing from the pressure-generating arc 26 through the several vents to the region externally of the unit 14. Also, the interrupting arc 27 engages a plentiful supply of oil retained in the pockets 37, 48, 66 and 80 as an additional source of gas and deionizing turbulence. The result is an extinction of the interrupting arc 27 at an early current zero and the building up of sufficient dielectric strength between the separated contacts 23, 25 to prevent restriking.

It will be observed that the radius arm R' between the upper movable contact 25 and the shaft 20 is greater than the radius arm R² between the lower movable contact 24 and the shaft 20. Consequently, by this difference in lever arm ratios, the speed of separation of the contacts 22, 25 is greater than the speed of operation of the contacts 23, 24 and the result is that the interrupting arc 27 is rapidly lengthened to a considerable length. Also, by this construction, the length of the pressure-generating arc 26 is controlled to prevent the attainment of excessive pressure thereat. Following interruption of the electrical circuit through the interrupter, the movable bridging member 12 separates from the disconnect fingers 15 to introduce two isolating gaps opening into the circuit, as indicated by the dotted lines in Fig. 1.

During the closing operation, the operating rod

13 moves upwardly causing an engagement between the movable bridging member 12 and the disconnect contacts 15 to cause thereby the raising of the cross-member 16 and the operating rods 17. The raising of the operating rods 17 causes a clockwise rotation of the several crank arms 19 about the shafts 20 to thus cause a clockwise rotation of the bridging contacts 21 to effect a re-engagement between contacts 22, 25 and 23, 24. The electrical circuit is then completed through the interrupter.

The arc-extinguishing units 14 are maintained in spaced superimposed axially aligned relation in a fixed manner by conducting supports generally designated by the reference numeral 95. The supports 95 also serve to support the stationary contact housings 28 and 29.

Three of the units 14 serially connected interrupted currents from 500 to 7000 amperes at 132 kv. with arcing times of only 1.2 to 1.9 cycles on 60 cycle circuits.

In the modification of my invention as shown in Figs. 21 and 22, there is provided a modified type of arc-extinguishing unit generally designated by the reference numeral 97. Associated with the stationary contact 22 of the upper arc-extinguishing unit 97 in Fig. 22 and with the lower stationary contact 23 of the lower unit 97 are arcing horns 98 jutting arcuately along the path of motion of the rotatable contact 21 to which transfer of one terminal of the pressure-generating arc 26 may be effected during high-current interruption to prevent the attainment of excessive pressure within the units 97. During low-current interruption, the length of the pressure-generating arc 26 will be substantially the same as the interrupting arc 27, since the contact arms are equal in length for this modification, and the arc 26 does not transfer to horn 98.

However, during the interruption of high current, the ionized gas bubble is sufficiently large to engage the arcing horn 98, providing a conducting path thereto which results in the transfer of the upper terminal of the pressure-generating arc 26 associated with the upper unit of Fig. 22 to the horn 98 to thereby shorten the length thereof. The length of the pressure-generating arc 26 during high-current interruption is thus controlled to minimize the pressure formed thereat. As previously mentioned, during low-current interruption the ionized gas formed adjacent the pressure-generating arc 26 is not sufficient to contact the arc horn 98 to provide a conducting path thereto, and the upper terminal of the pressure-generating arc 26 will remain fixed at the stationary contact 22. Consequently, during low-current interruption the pressure-generating arc 26 will extend and remain extended between the contacts 22, 25 to attain a length practically the same as the length of the interrupting arc 27. This considerable length attained by the pressure-generating arc 26 during low-current interruption will serve to increase the pressure formed thereat; whereas during high-current interruption the pressure-generating arc 26 will be shortened by transfer to the arcing horn 98 to minimize the pressure formed thereat.

If desired, magnetic means may be provided to bias the pressure-generating arc 26 toward the arcing horn 98, which magnetic biasing means may be more effective during high-current interruption than during low-current interruption. The magnetic means which I provide comprises a U-shaped insert 99 composed of magnetic ma-

terial, for instance iron, as more clearly shown in Fig. 21. During high-current interruption, the magnetic insert 99 biases the pressure-generating arc 26 toward the arcing horn 98 to facilitate the transfer of the upper terminal of the pressure-generating arc 26 thereto.

Figs. 21 and 22 also disclose a piston arrangement associated with the bridging contact 21 to facilitate low-current interruption. The piston arrangement comprises an insulating block 100 extending between two insulating levers 101 having their other ends pivotally mounted about a cylindrical bearing 102 having a hexagonal bore. The hexagonal bore of the cylindrical bearing 102 is provided to accommodate the hexagonal shaft 20. Consequently, the insulating levers 101 are free to rotate about the cylindrical bearings 102 regardless of the orientation of the bridging contact 21. Suitable biasing means, not shown, such as spring means encircling the shaft 20 may be provided to bias the insulating block 100 away from the contact 25. Thus the insulating block 100 associated with the bottom unit 97 of Fig. 22 will be held in its upper position as shown in the closed circuit position of the interrupter.

A lost motion connection includes a pin 103 which extends between two insulating levers 101 and travels in a slot 104 provided in the bridging contact 21 to determine the travel of the insulating block 100.

The operation of the modified type of arc-extinguishing units 97 associated with the modified type of arc-extinguishing assemblage 105 shown in Fig. 22 will now be described. During the opening operation, the insulating operating rod 17 moves downwardly to cause a counterclockwise rotation of the bridging contacts 21 about the shafts 20 to establish a pressure-generating arc 26 and an interrupting arc 27, as previously described. In the modified type of arc-extinguishing assemblage 105, venting out of the units 97 takes place in an alternate manner, that is, venting from the lowermost unit 97 takes place to the left and venting from the immediately adjacent disposed upward unit 97 takes place to the right. This alternate venting arrangement from the assemblage 105 prevents a combining of the exhaust gases from the several units 97 to minimize the hazard of high-voltage breakdown axially along the assemblage 105. Also, unnecessary flow through the stationary contact assemblies between units is minimized, since the pressure is approximately balanced between two adjacent pressure breaks or between two adjacent interrupting breaks.

During low-current interruption, the pressure generated at the pressure-generating arc 26 will be lower, and consequently may not be sufficient to send the requisite oil velocity adjacent the interrupting arc 27 to effect rapid extinction thereof. With the piston arrangement herein disclosed, the bridging contact 21 will pick up the insulating block 100 after approximately one-third of its rotative travel to carry the insulating block 100 with it and thus send oil flow by piston action toward the interrupting arc 27 to effect the extinction thereof. During high-current interruption, the pressure generated at the pressure-generating arc 26 will be sufficient to maintain the block 100 in its extended position away from the bridging contact 21, and the pressure generated at the pressure-generating arc 26 will act between the block 100 and the bridging contact 101 to effect extinction of the interrupting arc 27.

An additional function obtained by this piston arrangement is the attainment of a flushing action that will force clean oil through the unit 97 with each mechanical operation of the contacts. This flushing operation results in a mechanical operation of the breaker with no current passing therethrough, that is, during no-load operation. In other words, an opening stroke during such a mechanical no-load operation of the breaker will serve to cause the bridging member 21 to pick up the insulating block 100 and cause oil to flow out of the vents 106 in a manner similar to low-current interruption, and oil will be drawn in through the check valve 107. During the closing stroke on such a mechanical no-load operation of the interrupter, the insulating block 100 will be maintained in its extended position away from the bridging contact 21. As a result during repeated opening and closing no-load operations of the interrupter oil is drawn in through the check valves 107 and forced by piston action through the unit 97 and out the vents 106.

In the modified type of arc-extinguishing unit generally designated by the reference numeral 108 and shown in Figs. 23 and 24, I have provided an arcing horn 109 disposed at the upper end of the unit 108 and a second arcing horn 110 disposed at the lower end of said unit. Consequently, the pressure-generating arc 26 may run along the bridging contact 21 and the arcing horn 109. In like manner, the interrupting arc 27 may run along the bridging contact 21 and the upper arcing horn 109. Preferably, magnetic means are provided to bias the interrupting arc 27 laterally. The magnetic means which I utilize comprises a U-shaped insert 111 composed of magnetic material, in this instance iron.

By providing a construction wherein both the pressure-generating arc 26 and the interrupting arc 27 may move laterally, fresh oil is engaged by both of said arcs, interruption is facilitated and erosion of the fibre plates minimized. One or more of the U-shaped inserts 111 used in the unit 108 may be used in conjunction with the interrupting structure shown in Figs. 2 and 3 to facilitate the lateral movement of the interrupting arc 27 in the units 14 toward the restricted portions of the slots; however, this construction of utilizing magnetic means is not shown in Figs. 2 and 3.

Fig. 25 shows a modified type of contact construction associated with a modified type of arc-extinguishing unit generally designated by the reference numeral 113. In this modified type of construction, I utilize a first bridging contact 114 and a second bridging contact 115 which cooperate together to bridge the stationary contacts 22, 23. An operating arrangement for the first and second bridging contacts 114, 115 may 55 assume a form as shown in Fig. 26 of the drawings. In this operating arrangement, the operating rod 17 is pivotally connected at 18 to a crank arm 19 serving to rotate a pinion gear 116. The gear 116 meshes with gears 117, 118 which rotate shafts 119, 120. The shafts 119, 120 serve to rotate the first and second bridging contacts 114, 115 in the desired direction. The first and second bridging contacts 114, 115 have cooperable contact portions 121, 122 which, when separated, establish a pressure-generating arc 26. Each bridging contact 114, 115 separates from the stationary contacts 22, 23 to establish thereby two interrupting arcs 27. Pressure generated at the single pressure-generating arc 26 acts in the direction indicated by the arrows in Fig. 25 to effect

extinction of the two interrupting arcs 27 at the splitters 123 associated with the vents 124.

It will be observed that this construction shown in Fig. 25 attains maximum break distance in a group of serially connected contact gaps with a minimum overall length. It is evident that not only is the ratio of insulation to conducting material in the lengthwise direction very high when the contacts are open, but also the inertia of the rotating contacts 114, 115 is somewhat less than for straight line moving contacts. This permits a given contact opening speed to be obtained with less acceleration than in conventional designs.

It will be apparent from the foregoing embodiments of my invention that from the point of view of avoiding restriking or voltage breakdown, the construction is particularly advantageous since there are no overlapping potentials in the voltage gradient from one end of the multibreak arc extinguishing assemblage to the other. Furthermore, the stationary contacts are easily accessible and the movable contacts require no shunts at all. By employing different lever ratios the length of the pressure break distance to the interrupting break distance may be easily varied by changing the pivot location on the bridging contacts 21. It will be apparent from the foregoing description that the inertia of the rotating members is considerably reduced over conventional structures, and that the break distance is a maximum in the open circuit position with a minimum overall length of the assemblage. Also, I have shown both magnetic means and piston means for speeding up low-current interruption where the pressure generated at the pressure-generating arc is relatively low.

Although I have shown and described specific structures, it is to be clearly understood that the same were merely for the purpose of illustration and that changes and modifications may be made by those skilled in the art without departing from the spirit and scope of the appended claims.

I claim as my invention:

1. In a circuit interrupter, a stationary arc extinguishing assemblage including a plurality of stationary spaced axially aligned serially related arc extinguishing units, each unit being substantially enclosed to form a pressure-generating chamber and an interrupting chamber, means venting the interrupting chamber only laterally of the unit whereby the upper and lower ends of each unit are substantially closed, relatively stationary contact means for each unit including a pair of relatively stationary contacts disposed at the upper and lower ends of each unit, a rotatable shaft fixedly positioned intermediate the upper and lower ends of each unit so as to be spaced axially between the pair of stationary contacts, a lever-shaped bridging contact member for each unit mounted intermediate its ends upon the shaft, the bridging contact member establishing a pressure-generating arc adjacent one end thereof within the pressure-generating chamber, the bridging contact being cooperable with at least one of the stationary contacts to establish an interrupting arc adjacent the other end thereof within the vented interrupting chamber, disconnect means disposed adjacent one end of the stationary arc extinguishing assemblage including a movable disconnect member and a relatively stationary disconnect contact, an operating rod extending axially externally of the units, means connecting one end of the operating rod to the relatively stationary

disconnect contact, and means operatively connecting the operating rod to each of the rotatable shafts to simultaneously effect their rotation.

2. In a circuit interrupter, a substantially enclosed arc extinguishing unit defining a pressure-generating chamber and an interrupting chamber, a relatively stationary contact, a pair of lever-shaped movable contact members, a pair of rotatable shafts, each lever-shaped movable contact member being mounted intermediate its ends upon a rotatable shaft, means for simultaneously rotating the shafts in the same direction, the opening separating motion of one movable contact member establishing a pressure-generating arc adjacent one end thereof within the pressure-generating chamber and an interrupting arc adjacent the other end thereof within the interrupting chamber, and fluid flow passage means interconnecting the two chambers so that fluid under pressure from the pressure-generating arc may flow through the passage means into the interrupting chamber to effect the extinction of the interrupting arc therein.
- 15 3. In a circuit interrupter, an arc extinguishing unit defining a pair of interrupting chambers positioned adjacent opposite ends of the unit and a pressure-generating chamber disposed intermediate the ends of the unit, a pair of stationary contacts disposed in the interrupting chambers, a pair of rotatable shafts disposed in axially aligned relation with respect to the two stationary contacts, a pair of elongated movable contact members mounted intermediate their ends upon the pair of shafts, each movable contact cooperating with a stationary contact to establish an interrupting arc within an interrupting chamber, and the two movable contacts cooperating with each other to establish a pressure-generating arc within the pressure-generating chamber.
- 20 4. In a circuit interrupter, an arc extinguishing assemblage including a plurality of spaced arc extinguishing units disposed in axially aligned relation, each unit being substantially enclosed and defining a pair of interrupting chambers disposed at the upper and lower ends of each unit, laterally leading venting means for each interrupting chamber so that the two interrupting chambers
- 25 5. In a circuit interrupter, an arc extinguishing assemblage including a plurality of spaced arc extinguishing units disposed in axially aligned relation, each unit being substantially enclosed and defining a pair of interrupting chambers disposed at the upper and lower ends of each unit, laterally leading venting means for each interrupting chamber so that the two interrupting chambers
- 30 6. In a circuit interrupter, an arc extinguishing assemblage including a plurality of spaced arc extinguishing units disposed in axially aligned relation, each unit being substantially enclosed and defining a pair of interrupting chambers disposed at the upper and lower ends of each unit, laterally leading venting means for each interrupting chamber so that the two interrupting chambers
- 35 7. In a circuit interrupter, an arc extinguishing assemblage including a plurality of spaced arc extinguishing units disposed in axially aligned relation, each unit being substantially enclosed and defining a pair of interrupting chambers disposed at the upper and lower ends of each unit, laterally leading venting means for each interrupting chamber so that the two interrupting chambers
- 40 8. In a circuit interrupter, an arc extinguishing assemblage including a plurality of spaced arc extinguishing units disposed in axially aligned relation, each unit being substantially enclosed and defining a pair of interrupting chambers disposed at the upper and lower ends of each unit, laterally leading venting means for each interrupting chamber so that the two interrupting chambers
- 45 9. In a circuit interrupter, an arc extinguishing assemblage including a plurality of spaced arc extinguishing units disposed in axially aligned relation, each unit being substantially enclosed and defining a pair of interrupting chambers disposed at the upper and lower ends of each unit, laterally leading venting means for each interrupting chamber so that the two interrupting chambers
- 50 10. In a circuit interrupter, an arc extinguishing assemblage including a plurality of spaced arc extinguishing units disposed in axially aligned relation, each unit being substantially enclosed and defining a pair of interrupting chambers disposed at the upper and lower ends of each unit, laterally leading venting means for each interrupting chamber so that the two interrupting chambers
- 55 11. In a circuit interrupter, an arc extinguishing assemblage including a plurality of spaced arc extinguishing units disposed in axially aligned relation, each unit being substantially enclosed and defining a pair of interrupting chambers disposed at the upper and lower ends of each unit, laterally leading venting means for each interrupting chamber so that the two interrupting chambers
- 60 12. In a circuit interrupter, an arc extinguishing assemblage including a plurality of spaced arc extinguishing units disposed in axially aligned relation, each unit being substantially enclosed and defining a pair of interrupting chambers disposed at the upper and lower ends of each unit, laterally leading venting means for each interrupting chamber so that the two interrupting chambers
- 65 13. In a circuit interrupter, means defining a stationary substantially enclosed arc extinguishing unit, a pair of stationary contacts positioned at the upper and lower ends of the unit, the unit forming a pressure-generating chamber adjacent one stationary contact and an interrupting cham-
- 70 14. In a circuit interrupter, means defining a stationary substantially enclosed arc extinguishing unit, a pair of stationary contacts positioned at the upper and lower ends of the unit, the unit forming a pressure-generating chamber adjacent one stationary contact and an interrupting cham-
- 75 15. In a circuit interrupter, means defining a stationary substantially enclosed arc extinguishing unit, a pair of stationary contacts positioned at the upper and lower ends of the unit, the unit forming a pressure-generating chamber adjacent one stationary contact and an interrupting cham-

ber adjacent the other stationary contact, the upper and lower ends of the unit being substantially closed, laterally extending venting means leading from the interrupting chamber laterally out one side end of the unit, a rotatable shaft disposed intermediate the ends of the unit, a lever-shaped movable contact mounted intermediate its ends upon the shaft and having its ends making contacting engagement with the two stationary contacts, means for rotating the shaft and movable contact member so that the ends thereof separate substantially simultaneously in opposite directions from the two stationary contacts to simultaneously establish a pressure-generating arc within the pressure-generating chamber and an interrupting arc within the interrupting chamber, and fluid flow passage means interconnecting the two chambers.

6. In a circuit interrupter, a stationary arc extinguishing unit having the top and bottom thereof substantially closed, a pair of stationary contacts positioned adjacent the top and bottom of the unit, a rotatably mounted movable lever-shaped contact member positioned intermediate the ends of the unit with the ends thereof making contacting engagement with the stationary contacts in the closed circuit position of the interrupter, the unit defining a pressure-generating chamber adjacent one stationary contact and an interrupting chamber adjacent the other stationary contact, laterally extending venting means leading laterally out one side end of the unit from the interrupting chamber, means for rotating the movable contact so that the ends thereof separate simultaneously in opposite directions from the stationary contacts to establish a pressure-generating arc within the pressure-generating chamber and an interrupting arc within the interrupting chamber, a pair of laterally extending arc horns positioned adjacent the two stationary contacts, magnetic means for biasing the interrupting arc along one of the arcing horns toward the venting means, and fluid flow passage means interconnecting the two chambers.

7. In a circuit interrupter of the liquid break type, a substantially enclosed arc extinguishing unit submerged in a suitable arc extinguishing liquid, a pair of stationary contacts positioned adjacent opposite ends of the unit, the unit defining a pressure-generating chamber adjacent one stationary contact and an interrupting chamber adjacent the other stationary contact, a rotatable shaft positioned intermediate the ends of the unit, a movable lever-shaped contact mounted intermediate its ends upon the shaft and having the end portions thereof making contacting engagement with the two stationary contacts in the closed circuit position of the interrupter, means for rotating the shaft and movable contact to establish a pressure-generating arc within the pressure-generating chamber and an interrupting arc within the interrupting chamber, fluid flow passage means interconnecting the two chambers, a piston member loosely mounted upon the shaft, and a lost-motion connection between the piston member and the movable contact.

8. In a circuit interrupter, a stationary arc extinguishing assemblage including a plurality of stationary axially aligned arc extinguishing units disposed in spaced end-to-end relationship, a pair of stationary contacts positioned adjacent the opposite axial ends of each unit, a rotatable shaft extending through each unit intermediate the ends thereof, a lever-shaped movable contact

member disposed interiorly within each unit and mounted intermediate its ends upon the rotatable shaft, the end portions of each movable contact member making contacting engagement with the stationary contacts of the respective unit, the rotation of the shaft causing the ends of the movable contact member to separate simultaneously in opposite directions from the respective two stationary contacts of the particular unit, operating

10 rod means extending axially externally of the units to cause actuation of the assemblage, and means operatively connecting the rod means externally of the unit with each rotatable shaft to cause their simultaneous operation.

15 9. In a circuit interrupter, a stationary arc extinguishing assemblage including a plurality of stationary axially aligned arc extinguishing units disposed in spaced end-to-end relationship, a pair of stationary contacts positioned adjacent the opposite axial ends of each unit, the unit defining a pressure-generating chamber adjacent one stationary contact and an interrupting chamber adjacent the other stationary contact, a rotatable shaft extending through each unit intermediate the ends thereof, a lever-shaped movable contact member disposed interiorly within each unit and mounted intermediate its ends upon the rotatable shaft, the end portions of each movable contact member making contacting engagement with the stationary contacts of the respective unit, the rotation of the shaft causing the ends of the movable contact member to separate simultaneously in opposite directions from the respective two stationary contacts of the particular unit to establish simultaneously a pressure-generating arc within the pressure-generating chamber and an interrupting arc within the interrupting chamber, operating rod means extending axially externally of the units 30 to cause actuation of the assemblage, and means operatively connecting the rod means externally of the unit with each rotatable shaft to cause their simultaneous operation.

40 10. In a circuit interrupter, a stationary arc extinguishing assemblage including a plurality of stationary axially aligned arc extinguishing units disposed in spaced end-to-end relationship, a pair of stationary contacts positioned adjacent the opposite axial ends of each unit, one contact being on a higher level of the assemblage than the other contact, a rotatable shaft associated with each unit, a movable bridging contact mounted intermediate its ends upon the shaft to electrically interconnect the two stationary contacts, each unit defining a substantially confined pressure-generating chamber adjacent one stationary contact and a vented interrupting chamber adjacent the other stationary contact, passage means extending between the two chambers, the movable bridging contact separating from one stationary contact to establish a pressure-generating arc axially of the assemblage within the pressure-generating chamber and from the other stationary contact to establish an interrupting arc axially of the assemblage within the interrupting chamber, and means including an elongated operating rod movable axially of the assemblage for simultaneously rotating all the shafts of the assemblage.

70 11. In a circuit interrupter, a stationary arc extinguishing unit, a pair of stationary contacts disposed at opposite ends of the unit, the unit defining a substantially confined pressure-generating chamber adjacent one stationary contact

and a vented interrupting chamber adjacent the other stationary contact, a rotatable shaft, a movable lever-shaped contact member mounted intermediate its ends upon the shaft, the movable contact separating from one stationary contact to establish a pressure-generating arc within the pressure-generating chamber, the movable contact separating from the other stationary contact to establish an interrupting arc within the interrupting chamber, passage means interconnecting the two chambers, and a stationary arcing horn disposed adjacent to the stationary pressure-generating contact and jutting arcuately along the path of motion of the movable pressure-generating contact in closely spaced relationship therewith for an appreciable length of travel of said pressure-generating contact to which one terminal end of the pressure-generating arc may transfer only during high current interruption.

12. In a circuit interrupter, a substantially enclosed arc extinguishing unit defining a pressure-generating chamber and an interrupting chamber, a relatively stationary contact, a pair of lever-shaped movable contact members, a pair of rotatable shafts, each lever-shaped movable contact member being mounted intermediate its ends upon a rotatable shaft, means for simultaneously rotating the shafts in the same direction, the opening separating motion of one movable contact member away from the other movable contact member establishing a pressure-generating arc adjacent one end thereof within the pressure-generating chamber, the opening separating motion of the first-mentioned movable contact member away from the relatively stationary contact establishing an interrupting arc adjacent the other end thereof within the interrupting chamber, and fluid flow passage means interconnecting the two chambers so that fluid under pressure from the pressure-generating arc may flow through the passage means into the interrupting chamber to effect the extinction of the interrupting arc therein.

13. In a circuit interrupter, an arc extinguishing assemblage including a plurality of stationary substantially enclosed arc extinguishing units, a pair of stationary contacts positioned at the upper and lower ends of each unit, each unit forming a pressure-generating chamber adjacent one stationary contact and an interrupting chamber adjacent the other stationary contact, the upper and lower ends of each unit being substantially closed, laterally extending venting means leading from the interrupting chamber of each unit laterally out one side end of the unit, a rotatable shaft disposed intermediate the ends of each unit, a lever-shaped movable contact member mounted intermediate its ends upon the shaft and having its ends making contacting engagement with the two stationary contacts, means for rotating the plurality of shafts and movable contact members in unison so that the ends of the several contact members separate substantially simultaneously in opposite directions from the stationary contacts to simultaneously establish a plurality of pressure-generating arcs within the pressure-generating chambers and a plurality of interrupting arcs within the interrupting chambers, and fluid flow passage means associated with each arc extinguishing unit interconnecting the pressure-generating and interrupting chambers of that unit.

14. In a circuit interrupter, an arc extinguishing assemblage including a plurality of stationary

substantially enclosed arc extinguishing units, a pair of stationary contacts positioned at the upper and lower ends of each unit, each unit forming a pressure-generating chamber adjacent one stationary contact and an interrupting chamber adjacent the other stationary contact, the upper and lower ends of each unit being substantially closed, laterally extending venting means leading from the interrupting chamber of each unit laterally out one side end of the unit, a rotatable shaft disposed intermediate the ends of each unit, a lever-shaped movable contact member mounted intermediate its ends upon each shaft and having its ends making contacting engagement with the

10 two stationary contacts of the respective unit, an operating rod extending axially of the units for rotating the several shafts and the several movable contact members so that the ends of the movable contact members separate substantially

15 simultaneously in opposite directions from the stationary contacts to simultaneously establish thereby a plurality of pressure-generating arcs within the pressure-generating chambers and a plurality of interrupting arcs within the inter-

20 rupting chambers, and fluid flow passage means associated with each arc extinguishing unit interconnecting the pressure-generating and interrupting chambers of that unit.

15. In a circuit interrupter, an arc extinguishing

30 assemblage including a plurality of stationary substantially enclosed arc extinguishing units, a pair of stationary contacts positioned at the upper and lower ends of each unit, each unit forming a pressure-generating chamber adjacent one

25 stationary contact and an interrupting chamber adjacent the other stationary contact, the upper and lower ends of each unit being substantially closed, laterally extending venting means leading from the interrupting chamber of each unit lat-

30 erally out one side end of the unit, a rotatable shaft disposed intermediate the ends of each unit, a lever-shaped movable contact member mounted intermediate its ends upon each shaft and having its ends making contacting engage-

40 ment with the two stationary contacts of the respective unit, an operating rod extending axially of the units for rotating the several shafts and the several movable contact members so that the ends of the movable contact members sep-

45 arate substantially simultaneously in opposite directions from the stationary contacts to simulta-

50 neously establish thereby a plurality of pres-

ure-generating arcs within the pressure-gener-

55 ating chambers and a plurality of interrupting arcs within the interrupting chambers, fluid flow

passage means associated with each arc extin-

60 guishing unit interconnecting the pressure-gen-

65 erating and interrupting chambers of that unit, disconnecting means disposed adjacent one end

60 of the arc extinguishing assemblage including a movable disconnect member and a relatively sta-

70 tionary disconnect contact, means connecting one end of the operating rod to the relatively sta-

75 tionary disconnect contact, and means operative-

ly connecting the operating rod to each of the

rotatable shafts to simultaneously effect their

rotation.

16. In a circuit interrupter, a stationary arc extinguishing assemblage including a plurality of stationary axially aligned arc extinguishing units disposed in spaced end-to-end relationship, a pair of stationary contacts positioned adjacent the opposite axial ends of each unit, a rotatable shaft extending through each unit intermediate the ends thereof, a lever-shaped movable contact

member disposed interiorly within each unit and mounted intermediate its ends upon the rotatable shaft, the end portions of each movable contact member making contacting engagement with the stationary contacts of the respective unit, the rotation of the shaft causing the ends of the movable contact member to separate simultaneously in opposite directions from the respective two stationary contacts of the particular unit, operating rod means extending axially externally of the units to cause actuation of the assemblage, disconnect means disposed adjacent one end of the arc extinguishing assemblage including a movable disconnect member and a relatively stationary disconnect contact, means connecting one end of the operating rod means to the relatively stationary disconnect contact, and means operatively connecting the rod means externally of the unit with each rotatable shaft to cause their simultaneous operation.

WINTHROP M. LEEDS.
